INVENTOR

George L. Briggs.

UNITED STATES PATENT OFFICE

GEORGE L. BRIGGS, OF BROOKLYN, NEW YORK

VANITY CASE

Application filed December 29, 1928, Serial No. 329,261. Renewed September 30, 1930.

This invention relates to vanity cases, and more particularly to vanity cases and means for removably holding compacts therein.

It is an object of the invention to provide a vanity case of simple construction having a compact pad which may be easily and quickly inserted therein and expelled therefrom.

It is a further object of the invention to provide a case and compact such that the latter may be locked in place within the case and unlocked in a simple and effective manner.

A further object is to provide a vanity case which shall be of neat and attractive appearance and in which the component parts are few and such that it may be cheaply made and assembled.

It is a still further object to provide a case such that the base of the compact or pad may be arranged to cooperate only with the holding member in the case, so that only refills specially constructed to fit the case can be used therewith, whereby it becomes possible to insure that only compacts of a predetermined quality can be put in place in the case.

With these general objects as above stated and others not specifically referred to, the invention consists in the combinations, features, details of construction and arrangements of parts which will first be described in connection with the accompanying drawings and then more particularly pointed out in the claims.

In the drawings

Figure 1 is a plan view of a vanity case in open position, showing two compacts or pads with their respective coacting retainers or holding members partly in section.

Figure 2 is an edge view of the box closed. Figure 3 is a sectional view, enlarged, of one side of the box with a compact or pad in entering position.

Figure 4 is a sectional view, enlarged, taken on the line 4-4 of Figure 1.

Figure 5 is a sectional view, enlarged, taken on the line 5-5 of Figure 1.

Figure 6 is a sectional view, enlarged, taken on the line 6-6 of Figure 1.

Figure 7 is an enlarged sectional view of a modification.

Figure 8 is a bottom view, enlarged, of the compact in Figures 1-6;

Figure 9 is a bottom view, enlarged, of left side of Figure 1, with case removed, showing compact in unlocked position;

Figure 10 is a bottom view, enlarged, of holding member;

Figure 11 is a bottom view, enlarged, of right side of Figure 1 with case removed, showing compact in locked position;

Figure 12 is a sectional view, enlarged, taken on the line 12-12 of Figure 8;

Figure 13 is a sectional view, enlarged, taken on the line 13-13 of Figure 8;

Figure 14 is a sectional view, enlarged, taken on the line 14-14 of Figure 10;

Figure 15 is a sectional view, enlarged, taken on the line 15-15 of Figure 10.

Briefly described, the invention contemplates the provision of means for removably securing within a vanity case a compact or pad so that used compacts may be replaced by fresh compacts without the necessity of replacing the entire case.

Although this means may vary, it may advantageously comprise a holding member and a held member adapted to fit one within the other and to lock upon relative rotative motion and to unlock upon further relative motion.

While capable of various constructions, as here shown, locking and unlocking may be accomplished by providing the two coacting members with outlines having unequal overall dimensions, one of the members being such that its greatest overall dimension is equal to one of the lesser overall dimensions of the other member, so that the two members when arranged one within the other and relatively positioned with their equal dimensions coinciding, are locked, and when turned relatively to each other away from this coinciding position are unlocked.

Referring now to the drawings, the case chosen for purposes of illustration is shown as a double case, i. e., one having both its body and cover hinged together, and both adapted for holding articles such for example as compacts.

It is to be understood, of course, that the

case here shown is merely illustrative and that in its broader aspects the invention contemplates cases of widely varying forms and for widely varying uses.

5 Specifically, the case comprises two body or cover sections 1, 2, hingedly connected together as by a pintle 3, and hinge 4. While these cover sections 1, 2, may vary in construction, they are, as shown, identical, being 10 dished and having upstanding side walls which when closed may, if desired, be locked together by a snaplock shown conventionally at 6, 7. If desired, a single or double faced mirror 8 may be carried between the two 15 cover sections 1, 2. Since each of the cover sections are shown as identical, only one will be specifically referred to.

Suitably secured within body section, e. g. 1, is a holding member 9 having a central 20 aperture 10 surrounded by a wall 11, this member being formed by blanking and drawing a disc in a well-known manner.

This holding member with its central aperture 10 acts in the nature of a receiving 25 member for a toilet article 12. While capable of various constructions, the latter may comprise a powder or rouge compact 13 secured in any suitable manner to a compact base comprising a bottom portion 14 and a 30 side wall portion 15, over which the compact 13 extends to present a non-metallic upper surface to the user. This compact base is arranged to enter the central aperture 10 and means are provided for limiting the distance 35 that the base 14 may extend into the aperture 10. This may be accomplished by providing a seat for the compact base. While capable of many arrangements, in the best embodiment of the invention the construction is as 40 follows:

Between the upper surface 16 of the holding member 9 and the walls 11 of the aperture there is formed a beveled surface 17. For cooperating with this beveled surface or 45 seat 17 the wall portion 15 of the bottom portion 14 is beveled outwardly at an angle substantially equal to the angle of bevel of surface 17, so that this beveled portion 18, upon insertion of the compact base into the aperture 10, seats upon the beveled surface 17, not only limiting the movement of the base within the aperture but also tending to position it in place for locking, as will hereinafter more fully appear.

50 Means are provided for locking the compact base within the aperture 10 of the holding member 9. This may be accomplished by turning the parts into frictional engagement. To this end, the outlines of the walls 60 of holding member and the held member may be so designed as to have unequal dimensions, one of the smaller dimensions of the outer or holding member being substantially equal to the largest dimension of the coating portion 65 of the inner or held member, so that when

placed one within the other as shown in Figure 4, i. e. with the largest dimension of each in substantial coincidence, they may be freely separable, but when rotated so as to bring the substantially equal dimensions into coincidence, the side walls 11 and 15 in the vicinity of the large dimension become frictionally interlocked.

In the example shown, the compact base or held member 14, and the aperture 10 of the holding member 9, are elliptical in outline, the major axis or greatest dimension of the base 14 in a certain plane being of a value that is substantially equal to the minor axis 70 of the aperture 10 in the same plane.

Therefore, when the two members are relatively turned to bring their equal axes into coincidence, one within the other, their side walls frictionally engage and one is positively held within the other until released by 75 relative rotation to move the axes out of coincidence.

It has been found that frictional engagement between the side walls of the aperture may be made more positive if the walls are 80 given a bevel.

In the example shown, the side walls 15 of the base 14 are inwardly beveled (Figures 3, 4, 5), as at 19, 20, while the side walls 11 of the aperture 10 are correspondingly beveled 85 (Figures 5, 6) as at 20', 21.

While these walls may be beveled throughout their full peripheral extent, it has been found convenient from a manufacturing standpoint to bevel them only along the extent of their interengagement. In Figure 6, the walls 15 are not beveled, as indicated by reference character 22, while as shown in Figures 3, 4 and as indicated at 23, 24 the walls are not beveled.

Means are provided for holding the parts in locked engagement after they have been turned into position.

Although capable of various constructions, in the example shown, Figures 1 to 6, the parts are held together by means of a spring 25, which exerts its pressure between the inside of the body section 1 and the under surface of the base 14.

In the modification shown in Figure 7, the parts are held together by forming the angles of bevel of the side walls unequally. As there shown, the angle 26 between the side wall 15 and the bevel surface 27 of the flange 18 is less than the angle formed between the side wall 11 and the seat 17. The small angle of the compact thus acts in the nature of a spring upon the larger angle of the holder.

Means may be provided for ejecting the compact from its holder when the two are turned to unlocked position. This may be accomplished by spring means. In the example shown, the spring means for holding the parts together also perform the function of separating them when unlocked. In Fig-

ures 1 to 6, spring 25 exerts its pressure upon the under surface of the compact base 14, forcing it out upon disengagement, while in Figure 7 the spring effect of the unequal 5 angles upon retracting tends to separate the compact from the holder.

With this arrangement, it is found to be unnecessary to employ a knife or other sharp instrument for prying the compact loose 10 from its holding member when it is desired to refill. It is only necessary to give the parts a slight turn, whereupon they separate.

It is evident that the vanity case herein 15 set forth is simple and economical in construction, has few parts, and is free of objectionable detents, nibs, snap rings and similar devices so prevalent in cases heretofore in use.

While the invention has been illustrated 20 in a construction embodying all its features in the form now preferred, and certain modifications thereof, it will be understood that the invention is not limited to the specific construction and arrangements of parts 25 shown, but that many modifications other than those shown and described may be made by those skilled in the art, while retaining the invention defined by the claims.

It is to be noted that the two coating members herein above described have interlocking, sloping, peripheral surfaces and that the slopes of said surfaces vary peripherally with respect to a common axis of rotation.

What I claim is:

35 1. In a vanity case structure and in combination, a holding member substantially geometrically regular in outline and having axes of different dimensions and a held member substantially geometrically regular in outline 40 and having axes of different dimensions, said holding and held members being relatively rotatable, a recess in said holding member for receiving the held member, side walls for said recess and said held members, the overall dimension between the side walls of the held member, when measured along one of its axes, being substantially equal to the overall distance between the side walls of said recess when measured along one of its axes, the side 45 walls of the holding member being reversely beveled adjacent either end of their said axis to define inwardly projecting shoulders, and the side walls of the held member being similarly beveled adjacent either end of their 50 said axis, so that upon the rotation of the held member within said recess the shoulders of the holding member and the beveled side walls of said held member interengage to lock said members together.

60 2. In a vanity case structure and in combination, a holding member substantially geometrically regular in outline and having axes of different dimensions and a held member substantially geometrically regular in 65 outline and having axes of different dimen-

sions, said holding and held members being relatively rotatable, a recess in said holding member for receiving the held member, the upper surface of the held member defining an outwardly projecting peripheral flange, the upper surface of the holding member coacting with said flange to seat the held member relative to the recess, side walls for said recess and said held member, the side walls of said recess being reversely beveled 70 to define inwardly projecting shoulders, and the side walls of the held member being beveled, so that upon the rotation of the held member within said recess the shoulders of the holding member and the beveled side walls of said held member interengage to lock 75 said members together.

3. In a vanity case structure and in combination, a holding member substantially geometrically regular in outline and having axes of different dimensions and a held member substantially geometrically regular in outline and having axes of different dimensions, said holding and held members being relatively rotatable, a recess in said holding member for receiving the held member, side walls for said recess and said held member, the overall dimension between the side walls of the held member, when measured along one of its axes, being substantially equal to the 80 overall distance between the side walls of said recess when measured along one of its axes, the side walls of the holding member being reversely beveled adjacent either end of their said axis to define inwardly projecting shoulders, and the side walls of the held member being similarly beveled adjacent either end of their said axis, so that upon the rotation of the held member within said recess the shoulders of the holding member and the beveled side walls of said held member interengage to lock said members together, and means for retaining the held and holding members in position when so locked.

4. In a vanity case structure and in combination, a holding member substantially geometrically regular in outline and having axes of different dimensions and a held member substantially geometrically regular in outline and having axes of different dimensions, said holding and held members being relatively rotatable, a recess in said holding member for receiving the held member, the upper surface of the held member defining an outwardly projecting peripheral flange, the upper surface of the holding member coacting with said flange to seat the held member relative to the recess, side walls for said recess and said held member, the side walls of said recess being reversely beveled to define inwardly projecting shoulders and the side walls of the held member being beveled, so that upon the rotation of the held member within said recess the shoulders of the holding member and the beveled side walls 120 125 130

of said held member interengage to lock said members together, and means for retaining the held and holding members in position when locked.

5. In a vanity case structure and in combination, a holding member substantially geometrically regular in outline and having axes of different dimensions and a held member substantially geometrically regular in outline and having axes of different dimensions, said holding and held members being relatively rotatable, a recess in said holding member for receiving the held member, side walls for said recess and said held members, the overall dimension between the side walls of the held member, when measured along one of its axes, being substantially equal to the overall distance between the side walls of said recess when measured along one of its axes, the side walls of the holding member being reversely beveled adjacent either end of their said axes to define inwardly projecting shoulders, and the side walls of the held member being similarly beveled adjacent either end of their said axis, so that upon rotation of the held member within said recess the shoulders of the holding member and the beveled side walls of said held member interengage to lock said members together, and means for retaining the held and holding members in position when locked and for separating said members when unlocked.

6. In a vanity case structure and in combination, a holding member substantially geometrically regular in outline and having axes of different dimensions and a held member substantially geometrically regular in outline and having axes of different dimensions, said holding and held members being relatively rotatable, a recess in said holding member for receiving the held member, the upper surface of the held member defining an outwardly projecting peripheral flange, the upper surface of the holding member coacting with said flange to seat the held member relative to the recess, side walls for said recess and said held member, the side walls of said recess being reversely beveled to define inwardly projecting shoulders, and the side walls of the held member being beveled, so that upon the rotation of the held member within said recess the shoulders of the holding member and the beveled side walls of said held member interengage to lock said members together, and means for retaining the held and holding members in position when locked and for separating said members when unlocked.

7. As a new article of manufacture, a compact pad, side walls therefor, said side walls extending first inwardly beneath the surface of the compact to define a peripheral flange therefor and then diverging part way their peripheral length as they approach the lower

surface of the compact to form the base of the compact.

8. As a new article of manufacture, a compact pad, inwardly extending side walls defining a peripheral flange therefor, said side walls at oppositely disposed points, part way their peripheral length, being thereafter reversely beveled to define a pair of outwardly projecting shoulders merging into the lower surface of the compact to form the base of the compact.

9. In a vanity case structure and in combination a holding member and a held member, said members being relatively rotatable, a recess in one of said members for receiving the other, side walls for said member and said recess, said side walls being beveled at unequal angles so that upon insertion of said member into said recess and relative rotation thereof, said beveled walls frictionally engage and hold said members locked in engagement.

10. As a new article of manufacture, a compact pad, side walls therefor, the peripheral edge of said walls defining a substantial ellipse, said walls extending first inwardly beneath the surface of the powder or rouge to define a peripheral flange and then diverging part way their peripheral length as they approach the base of the compact pad.

11. As a new article of manufacture, a compact pad, inwardly extending side walls defining a peripheral flange, the edge of said side walls following substantially the outline of an ellipse, said side walls near the ends of their major axis being beveled to define outwardly projecting shoulders merging into the lower surface of the compact.

12. In a vanity case structure and in combination an elliptical bevelled holding member, an elliptical bevelled recessed held member, side walls for both said members, the major axis of said held member being substantially equal to the minor axis of said holding member, so that, upon the insertion of said held member within said recessed holding member, with the major axes in substantial coincidence, said members are separable, and upon relative rotation of said members to bring the equal axes into coincidence said held member is locked within said holding members.

13. In a vanity case structure and in combination, a holding member substantially geometrically regular in outline and having axes of different dimensions, a held member substantially geometrically regular in outline and having axes of different dimensions, said holding member being recessed, the walls of said recess and of said held member being beveled to provide bearing surfaces between the two members for rotation, the overall dimension of the held member measured along one of its axes in a certain plane being substantially equal to the overall dimension of

the recess of the holding member in the same plane, so that upon relative rotation to cause the axes to approach coincidence said members lock together in frictional engagement.

5 14. A vanity case including a holding member and a cooperating held member, said members having interlocking sloping peripheral surfaces, one being an internal surface, the other being an external surface, said members 10 being relatively rotatable in either direction about a common axis to effect interlocking thereof, and the slopes of said surfaces varying peripherally with respect to said axis.

15 15. A vanity case including a holding member and a cooperating held member, said members having interlocking sloping peripheral surfaces, one being an internal surface, the other being an external surface, said members being relatively rotatable in either 20 direction about a common axis to effect interlocking thereof, and the slopes of said surfaces varying peripherally with respect to said axis and there being for any slope measured at any point on either surface at least 25 one other equal slope measured at another point on that surface.

30 16. A vanity case including a holding member and a cooperating held member, said members having interlocking sloping peripheral surfaces, one being an internal surface, the other being an external surface, said members being relatively rotatable in either direction about a common axis to effect interlocking thereof, and the slopes of said 35 surfaces varying peripherally with respect to said axis, said surfaces having line contact at a plurality of points when said members are interlocked.

40 17. A vanity case including a holding member and a cooperating held member, said members having interlocking sloping peripheral surfaces, one being an internal surface, the other being an external surface, said members being relatively rotatable in either 45 direction about a common axis to effect interlocking thereof, and the slopes of said surfaces varying peripherally with respect to said axis, said surfaces having line contact at a plurality of equally spaced points when 50 said members are interlocked, each line of contact being in some plane containing said axis and sloping toward said axis in the direction in which relative movement of said members is prevented by their interlocking.

55 18. A vanity case including, in combination, a holding member and a held member, said members being relatively rotatable and having substantially regular coacting outlines forming interengaging bevelled surfaces interlocking upon rotation about a common axis.

60 19. A vanity case including a holding member and a cooperating held member, said members having substantially regular coacting outlines forming interengaging bevelled

surfaces, said members having axes of different dimensions, and said members interlocking by rotation of one with respect to the other about a common axis.

70 In testimony whereof, I have hereunto set my hand.

GEORGE L. BRIGGS.
